(57) CLAIM

The ornamental design for a travel bag, as shown and described.

DESCRIPTION

FIG. 1 is a front perspective view of a first embodiment of the travel bag claimed herein;

FIG. 2 is a front plan view thereof;

FIG. 3 is a back plan view thereof;

FIG. 4 is a left side plan view thereof;

FIG. 5 is a right side plan view thereof;

FIG. 6 is a top plan view thereof; and,

FIG. 7 is a bottom plan view thereof.

The broken line showing of portions of the travel bag is included for the purpose of illustrating unclaimed subject matter and forms no part of the claimed design.
